ABSTRACT OF THE DISCLOSURE

Air-burst fuze system for functioning an explosive projectile in flight along a curved trajectory. Gyroscopic control means having a fixed axis of rotation with respect to the projectile in the plane of the trajectory is connected coaxially with annular rheostatic control means fixed to the projectile for increasing an initial preset triggering voltage on a firing diode in circuit with an electric detonator element. The latter is moved to an arm position in response to set back at launching.

The present invention relates to a stand-off control or fuze system for functioning an explosive or armed space vehicle, such as a projectile, a predetermined distance from an objective or target area. Various fuze systems of this type have been proposed in the past.

It is an object of this invention to provide an improved system for functioning a projectile in the air prior to contact with a target.

It is a further object of this invention to provide an improved air-burst fuze system wherein functioning occurs when a pre-selected angle of traverse of the projectile with respect to the firing angle has been met. As the projectile follows its trajectory it traverses an angle with respect to a gyroscope in the fuze which maintains a fixed attitude with respect to the original direction or firing angle.

It is also an object of this invention to provide an improved stand-off or airburst control system of the type referred to, which includes simple means for selectively functioning the projectile for airburst at any desired time or flight angle.

Military and like requirements in this field have presented problems in the past which have been solved by the use of mechanical, electrical and pyrotechnic time fuzes and by proximity fuzes operated by radio signals.

These older ways are and have been costly, inaccurate or unreliable in many instances and subject to being defeated by counter-measures.

In accordance with the system of the present invention an air burst can now be provided accurately, reliably and inexpensively. The time of flight is no limiting factor. Theoretically the projectile can be flying for an indefinite period before the selected traverse angle need be met.

No clock work is required and the number of components is greatly reduced. The device cannot be defeated by counter-measures, as a radio signal fuze can be defeated, it does not require the use of pyrotechnic powders, and it can be hermetically sealed to provide a long shelf life.

Further in accordance with the invention, the explosion initiating train of the projectile includes an electric detonator which receives firing current through a ground series firing circuit in which are provided an electrical energy source or pack, a triggering diode device, gyroscope and manually adjustable rheostat control elements and an arming switch or like safety device.

A fuze body is provided as a housing for the fuze system and may comprise the forward or nose cone end of

2

the projectile. A gyroscope flywheel is pivotally mounted in an inner ring-element which, in turn, is pivoted in an outer ring element at right angle to its pivot axis. The axis of the gyroscope and the pivot axis of the outer ring element are aligned with the spin axis of the projectile at the time of launching. The gyroscope flywheel and the inner ring unlock from the outer ring on launching and the relative movement controls the gyroscope rheostat to vary the impedance of the firing circuit as the gyroscope flywheel maintains attitude at takeoff with respect to earth during flight.

Thus as the angle of the gyroscope flywheel diverges from the spin axis of the projectile in flight, the resistance or impedance of the firing circuit is reduced and the voltage drop across the triggering diode increases until it closes to deliver the full firing current to the detonator, thus initiating the explosive train of the projectile. By adjusting the initial impedance or resistances by the manual setting rheostat to different values, the projectile may be set to function at different points along the trajectory, effectively providing selectable air burst therealong.

The invention will further be understood from the following description of a present preferred embodiment thereof, when considered with reference to the accompanying drawings, and its scope is pointed out in the appended claims.

In the drawings, FIGS. 1 and 2 are plan views, partly in section, of the nose cone of a projectile provided with an air-burst fuze system in accordance with the invention, the two figures being taken at right angles one with respect to the other,

FIG. 3 is an enlarged view of a portion of FIG. 2 showing the operational relation of certain elements thereof, further in accordance with the invention, and

FIG. 4 is a schematic circuit diagram of a firing circuit for the system showing certain elements of the preceding figures therein, for operation in accordance with the invention.

Referring to the drawings, in which like elements in the four figures are designated by like reference numerals, and referring particularly to FIGS. 1 and 2, the body or housing for the fuze system is the forward end or nose cone 10 of a space vehicle, such as an explosive projectile in the present example. The fuze housing is thus tapered longitudinally and provided with interior means for mounting the various elements in predetermined relation.

These elements include a gyroscope mechanism fixed in the fuze housing or nose cone, and comprising an outer pivot ring or ring element 14, an inner pivot ring or ring element 15, and an inner gyroscope flywheel 16, mounted on pivot axes y—y, x—x and z—z, respectively. The axis of the nose cone or housing 10, that is, the spin or longitudinal axis of the projectile, is the same as the y—y axis of the outer ring which thus rotates in coaxial relation to the nose cone and the projectile.

As viewed in FIG. 1 it will be seen that the outer ring 14 and the inner ring 15 lie in the same plane, with the outer ring pivoted to move on the axis y—y which is in alignment at all times with the direction of flight or longitudinal axis of the projectile. The inner ring 15 is pivoted on the x—x axis in the outer ring 14 at a right angle to the y—y and z—z axis. The inner ring thus can move on the axis x—x with respect to the outer ring which must follow the direction of flight of the carrier 10 on the axis y—y.

The outer ring 14 is the outer support member of the gyroscope. It is connected with the nose cone of housing 10 by longitudinally-spaced front and rear (or upper and lower) brackets 11 and 11A between which it is pivoted on the longitudinal or y—y axis of the housing or nose

cone and which extend across the interior of the nose cone and are secured to the inner wall thereof as indicated in FIG. 2. Any other suitable mounting means for the gyroscope elements which are firmly connected with the housing and provide pivot bearings for the outer ring, as described, may be used.

In coaxial relation to the axis $x-x$ is an annular mounting ring 17A carrying a semi-circular variable resistor or rheostat element 17 on its inner face in the plane of movement of the inner ring. The ring or carrier 17A for the resistor element 17 is connected with and affixed to the outer ring 14 at a right angle thereto through the axis $y-y$ and is coaxial with the inner ring 15 on the common axis $x-x$. The inner and outer rings 15 and 14 are pivoted on axes which are 90° displaced one from the other. The carrier or projectile 10 can spin around the axis $y-y$ while the outer ring 14 being pivoted on the same axis may remain stationary with respect thereto.

Both the outer and the inner rings are pivoted at the top and bottom, but are displaced 90° from one another. The outer pivot ring can rotate on its pivots around the axis $y-y$ of the fuze. The fuze body or housing 10 provides bearing points for the pivots of the outer pivot ring as above noted. The outer pivot ring provides bearing points for the inner ring 15. An orienting mass (not shown) may be provided on the outer ring to maintain the axis around which the inner ring pivots in a plane tangent to the earth's surface when the projectile is fired from the launcher. The outer pivot ring also provides the gyroscope rheostat 17 (variable resistance) surface required by the device. The pivots also provide the part of the circuit required.

Referring to FIG. 3, the inner pivot ring 15 is the inner support member which pivots inside the outer pivot ring 14. It provides bearing points for the gyroscope flywheel 16 and it also provides part of the circuit required. It provides the gyroscope contact 18 which rides along the resistor element 17 as the relative positions of axes $y-y$ and $z-z$ traverse the arc or angle $y-z$. Magnetic attraction or other biasing force between segments of 15 or 16 and 14 maintains axes $y-y$ and $z-z$ in line until the projectile is fired. Firing removes the magnetic attraction and permits traverse of the gyroscope flywheel 16 with respect to the outer pivot ring 14, as above described.

The gyroscope flywheel 16 consists of several parts which perform the following operation: Its axis of rotation $z-z$ remains aligned with axis $y-y$ of the fuze (and projectile) due to magnetic attraction or other biasing force until the launching gun is fired at which time the force alignment is removed and divergence of the axis $z-z$ from the axis $y-y$ is possible; setback in the projectile, upon firing, causes separation and counter-rotation of upper and lower portions of the flywheel which keeps the two portions apart; decay of counter-rotation below a certain value causes the two portions to come together, as they were prior to firing; the flywheel may provide the magnetic attraction which keeps the axes $z-z$ and $y-y$ aligned prior to firing; and the gyroscope flywheel maintains its attitude at firing with respect to earth during flight.

Referring to FIG. 4 along with the preceding figures, the gyroscope rheostat 17 is the portion of the outer pivot ring 14 which provides, in the firing circuit 25, the variable resistance in conjunction with the gyroscope contact 18 and the angle of traverse $y-z$ or movement of the contact along the rheostat resistor 17, and means for translating this traverse angle or movement into a useful signal by varying the firing circuit impedance or resistance.

The adjustable rheostat 19, with its movable contact 24, is the variable resistance in the firing circuit which is selected or set at firing and in conjunction with the gyroscope rheostat 17-18, permits selectable translation of traverse angle $y-z$ into angle of fall, which in turn, can be the point of air burst. The adjustable rheostat is

calibrated in angles of traverse or other related data for setting the airburst and is selectable externally.

The arming rotor 20 provides the mechanical out-of-line safety required of the detonator 21 as well as safety switching therefor by means of the series arming switch 5 27. Upon arming of the rotor the detonator 21 is aligned with the explosive train and is connected electrically in the firing circuit 25 by the switch 27.

The electric detonator 21 is the explosive train initiator. Safety requirements dictate that it will be out-of-line 10 until the projectile leaves the launching area in order to provide the utmost safety during manufacture, storage, handling and firing.

It may be noted here again that the axis $x-x$ is that 15 around which the inner pivot ring 15 rotates relative to the outer ring 14 and the resistor mounting. The $y-y$ axis is that around which the outer pivot ring 14 rotates relative to the housing or projectile, and it is also the long axis of the projectile 10. Therefore it coincides with the angle of elevation of the launching gun and the angular direction at takeoff. The axis $z-z$ is that around which the gyroscope flywheel 16 rotates, and the axis $R-R$ is that around which the rotor 20 rotates.

Referring more particularly to FIG. 4 and the firing 20 circuit 25, the operation is as follows: The setting rheostat 19 is adjusted to a value which, in addition to that of the rheostat, equals the circuit resistance required to close the diode 13 when the energy source 12 is at the desired voltage. Then when the source 12 is charged to 25 the desired voltage on setback, and the resistance of the gyroscope rheostat reduces to the value which, in addition to the resistance of the setting rheostat 19 causes the diode 13 to trigger and close, the source voltage then initiates the detonator 21 and the projectile functions.

30 A direct comparison between this system and those presently known and used clearly indicates that it represents a radical departure from conventional fuzes and conventional ways of solving the problem of reliable air-burst control. Alternative methods of construction in accordance with the invention may include the following features:

(a) The pivots of the inner and outer pivot rings 35 may not here be used as conductors in the firing circuit. The pivots may be resilient to telescope or otherwise give upon setback in order to remove the load from the bearings and transfer it to other members until the setback force subsides.

(b) Suitable magnetic aligning means may be included 40 in the shaft portion 28 of the gyroscope flywheel or in appropriate portions of the outer pivot ring, which here is of magnetic material, to maintain the axis $z-z$ in line with axis $y-y$ until the device is fired. When fired, the lower portion of the gyroscope flywheel is displaced from the influence of the corresponding magnets in the outer pivot ring and alignment is not maintained, permitting divergence of axis $z-z$ from axis $y-y$. In the present system the inner ring 15 is nonmagnetic.

(c) Movement of the axis $z-z$ with respect to the axis 45 $y-y$ or the operating angle $y-z$ and rheostatic control can be geared to magnify the excursion and thereby make it more accurate. Thus, the length, and therefore the accuracy, of the rheostat 17 may be increased as required.

(d) The gyroscope flywheel 16 can be made of two 50 portions—the upper which is fixed to gyroscope shaft 28 and the lower which is separate from both the upper portion and the shaft. Rotation of the lower portion can be stopped by transferring its rotative energy to the projectile body by momentary engagement therewith.

(e) The setting of the adjustable rheostat is translated 55 into distance along the trajectory, angle of traverse, time, or other useful or suitable units of measure. The contact 18 is shown as a wiper-type, but it can be a wheel, brush or other suitable element.

The rotor 20 is shown in simple cylindrical form for

the reason that delayed arming and self-sterilization features with a cylindrical type rotor are known and used in projectiles of this type. The axis of rotation may be parallel with, instead of perpendicular to, the axis y—y. The rotor element is thus shown only by way of example along with the remainder of the initiating train. Any suitable driving means may be used with the electric detonator 21 on the present fuze system. Also it will be seen that because there is only an electric circuit connecting the adjustable rheostat 19 with other parts of the circuit, the latter may be hermetically sealed for long shelf life.

The operation of the airburst fuze system is as follows: Setback forces cause counter-rotation of the upper and lower portions of the gyroscope and the arming means 20. Rotation of the flywheel fixes the position of axis z—z with respect to earth. Thus, in the launching means the axes y—y and z—z coincide. After launching and in flight as the projectile proceeds along its trajectory, the axis y—y will diverge from the axis z—z and the resistance of the element 17 will decrease. The y—y and z—z axes diverge because, although the gyroscope maintains the axis z—z in fixed relationship to the earth, the axis y—y does not maintain a fixed relationship with respect to earth but, instead, follows the trajectory of the projectile, thereby causing the axis z—z to diverge from the axis y—y. This divergence is the traverse angle y—z. When the resistance of the control element 17 is reduced to a certain value in conjunction with the resistance of the element, it causes sufficient voltage drop across the diode 3 to trigger and close it.

When the diode 13 closes it initiates the detonator 21 and functions the projectile. Adjusting the resistor 19 to different values causes the functioning of the projectile at different points and effectively provides selectable airburst along the trajectory which can be calibrated in suitable units as hereinbefore pointed out.

From the foregoing description, it will be seen that, with the system of the present invention, air-burst can be provided with accuracy at set points along the trajectory reliably and at relatively low cost. The fuze system is adapted to be housed in the forward end or nose of a conventional form of explosive projectile or the like. The latter may travel for any period or distance before the selected traverse angle occurs. No clock work timing means is required and the number of components used is reduced effectively to a minimum. The system cannot be actuated, that is defeated by counter-measure signals or other counter-measure means, as a radio-signal controlled fuze system can be actuated, it does not require the use of pyrotechnic or other light generating means, and is adapted for hermetic sealing for long stand-by use or storage.

I claim:

1. An air burst fuze system for the functioning of an explosive projectile in flight along a curved trajectory in accordance with a selected pitch or angular position therein, comprising in combination, a housing therefor, an electric detonator movable from a safe to an armed position in response to movement of said projectile into flight, an arming switch connected with said detonator to be moved therewith from an open unarmed position to the closed armed position, a firing circuit for the detonator connected or to be energized through said switch

and including a series triggering diode device effective to conduct firing current to said detonator at a predetermined higher triggering voltage applied thereto, series variable resistance means of annular ring form connected in circuit with said diode device to control and set the initial voltage level applied thereto, and gyroscopic control means having a fixed axis of rotation in the plane of the trajectory connected in coaxial relation with said resistance means to effect variations thereof and an increase in said applied voltage to the triggering level in response to movement of the projectile in flight through said selected pitch and angular position along said trajectory, thereby to initiate the functioning of said projectile.

2. An air-burst fuze system as defined in claim 1, wherein the gyroscopic control means includes inner and outer mounting rings relatively movable on pivot axes carrying relatively movable elements of the variable resistance means, and wherein the outer ring is adapted to be connected with the housing and the inner ring is fixed with respect to the said fixed axis of rotation of the gyroscope control means.

3. An air-burst fuze system for an explosive projectile in flight in a curved trajectory over a terrain area with changing pitch or flight angle comprising in combination, an electric detonator for initiating the explosive action of said projectile, means providing a source of electric energy having a voltage output effective to fire said detonator, a firing circuit for said detonator connected between said energy source and the detonator, said circuit including a triggering diode device together with an arming switch and a variable resistor device in series relation, means for closing said arming switch and moving said detonator from a safe to an operative position in response to setback action of said projectile, a gyroscope flywheel mounted to rotate in a plane transverse with respect to the spin axis of said projectile, pivotal mounting means for said flywheel comprising an outer pivot ring element having a pivot axis adapted to be fixed in and carried by said projectile in co-axial relation with the spin axis thereof and an inner pivot ring element mounted within the outer pivot ring element on a pivot axis at a right angle to and in the plane of the pivot axis thereof for relative rotation in response to change in pitch of the projectile in flight to maintain the gyroscope flywheel independent thereof and in a fixed initial attitude with respect to the terrain and the initial flight direction, means connected with said resistor device to vary the resistance of the firing circuit corresponding to relative movement of the said inner and outer ring elements with changes in pitch of said projectile in flight thereby to vary the effective voltage applied to the triggering diode device and to apply firing energy to the detonator therethrough with increased voltage to the break down point thereof corresponding to a desired point on the trajectory.
